UNITED STATES PATENT OFFICE

WILLIAM EARLE WARREN, OF BERKELEY, CALIFORNIA, ASSIGNOR, BY MESNE ASSIGNMENTS, TO KRIMPWIRE COMPANY, OF OAKLAND, CALIFORNIA, A CORPORATION OF CALIFORNIA

WIRE-MESH REINFORCEMENT

Application filed August 18, 1924. Serial No. 732,666.

This invention relates to a method and means of applying wire mesh to walls of buildings or other surfaces to form a medium for bonding plastic material to the wall.

Prior to my invention it has been common practice to secure wire mesh at a spaced distance from a wall to form a plaster key or bond. This has been accomplished by stretching the wire mesh over furring strips on the wall, or by securing the mesh to the wall by special nails having spacing shoulders thereon to hold the wire at a proper distance from the wall. These prior methods involved considerable labor in properly stretching the wire mesh and were, therefore, comparatively expensive.

The principal object of the present invention is to provide a generally improved method and means by which wire mesh may be properly and inexpensively applied to building walls to act as a desirable key or bonding medium for plastic coatings. In accomplishing this object I form the wire mesh with spaced channel or V-shaped ribs of a depth equal to the desired spacing between the mesh and the wall to which it is applied. When applying the wire mesh to a wall or surface, nails are inserted through the wire mesh laterally of the ribs and driven in on an angle. They are then bent over, thereby contracting the ribs and drawing the wire mesh taut.

To more fully illustrate the invention, reference is made to the accompanying specification and drawings, in which,

Fig. 1 is a cross-section of a portion of a wall structure, showing the application of the wire mesh.

Fig. 2 is a perspective view of one form of wire mesh employed showing it applied to a wall surface.

Referring to the drawings in detail, and particularly to Fig. 1, 1 indicates the studding of a wall structure such as employed in partitions and exterior walls of a building, 2 the exterior sheathing nailed or otherwise applied thereto, 3 ordinary wood lath nailed to the inner surface of the studding, and 4 plaster secured by means of the wood

lath. It might here be stated that wood lath is commonly employed for interior finish, but metal lath of one form or other is usually required where exterior surfaces are to be plastered. A great variety of metal lath is used, but the most common form is a wire mesh such as employed for fencing chicken yards and the like. This wire mesh must be spaced from the exterior surface or sheathing to form a key or bond for the plaster, and furring strips must, therefore, be interposed between the wire mesh and the sheathing, or special nails having shoulders or like devices must be employed. These features are objectionable, as they require time and labor and thereby increase expense.

The present invention contemplates the use of an ordinary wire mesh such as shown in Fig. 2. The wire mesh is passed through a set of rolls or the like in which are formed ribs and cooperating channels. The wire in being passed between these rolls is crimped or ribbed as indicated at 5, and these ribs serve two functions, first that of spacing the wire mesh with relation to the surface of the sheathing, and secondly that of permitting tightening of the wire mesh when applying the same. The ribs may be of any suitable shape, such as V-shaped or channel-shaped as here shown.

The work of applying the mesh to a wall surface is accomplished as follows: The wire mesh is fastened at one end and is then stretched over the surface to be covered. Nails are driven through the mesh and into the sheathing on an angle, as indicated at 6, (see Fig. 1) and the nails are then bent over as indicated at 7. This bending over of the nails pulls the wire taut between each set of ribs and as this work is quickly and easily accomplished, it can readily be seen that a minimum of labor and time is required, thereby materially reducing the cost of applying the same and at the same time insuring a taut application of the wire. The ribs are slightly contracted when the nails are bent over and the wire tightened as shown at 8, and it is therefore obvious that it is of some importance that the width of

the ribs be sufficient to permit such contraction. The ribs also serve to strengthen and stiffen the wire, thereby further facilitating its application.

5 While a specific form of wire mesh is shown in Fig. 2, it should be understood that any form of mesh may be employed without departing from the spirit of the present invention.

Having thus described my invention, what I claim and desire to secure by Letters 30 Patent is—

30 Patent is— A medium for bonding plastic material to a wall, consisting of wire mesh having twisted and untwisted strands forming interstices, said mesh having crimps formed 35 at intervals therein to space it out from the wall, the crimps being formed partially in the twisted strands and partially in the untwisted strands, whereby two untwisted strands provide two legs at one side of the 40 crimp and a single twisted strand provides one leg at the opposite side of the crimp, the twisted strands forming an angle at the top and closely adjacent to one side of the crimp to receive a fastening device.
